FOREIGN PATENT DOCUMENTS

AT 150784-0005 * 3/2004

Primary Examiner—T. Chase Nelson*Assistant Examiner*—Karen Acker(74) *Attorney, Agent, or Firm*—McGinn IP Law Group, PLLC(57) **CLAIM**

The ornamental design for a nut, as shown and described.

DESCRIPTION

FIG. 1 is a perspective view of the front, left side and top of a nut showing our new design;

FIG. 2 is a perspective view of the front, left side and bottom thereof;

FIG. 3 is a front view thereof;

FIG. 4 is a rear view thereof;

FIG. 5 is a top plan view thereof;

FIG. 6 is a bottom view thereof;

FIG. 7 is a left side view thereof; and,

FIG. 8 is a right side view thereof.

The elements shown in broken lines are for illustrative purposes only and form no part of the claimed design.
